UNITED STATES PATENT OFFICE

167,382

CHECKERBOARD

George F. Wales, Kenmore, N. Y.

Application October 17, 1951, Serial No. 17,000

Term of patent 14 years

(Cl. D34—5)

To all whom it may concern:

Be it known that I, George F. Wales, a citizen of the United States, resident of Kenmore, in the county of Erie and State of New York, have invented a new, original, and ornamental Design for a Checkerboard, of which the following is a specification, reference being had to the accompanying drawings, forming a part thereof. This specification is a continuation-in-part of application Serial No. D. 8,580, filed March 17, 1950 and which is now abandoned.

In the drawings:

Figure 1 is a plan view of a checkerboard embodying my new design illustrated in open position.

Figure 2 is an end elevation thereof.

Figure 3 is a perspective view of the checkerboard in its closed position; and

Figure 4 is a side elevation thereof in open position.

The essential features of my design are shown in full lines.

I claim:

The ornamental design for a checkerboard, substantially as shown and described.

GEORGE F. WALES.
